UNITED STATES PATENT OFFICE.

ANTHONY DIXON BROGAN AND ANDREW MURRAY MALLOCH, OF GLASGOW,
SCOTLAND.

DESIGN FOR AN ORNAMENTED SHEET OR PLATE OF GLASS.

SPECIFICATION forming part of Design No. 33,344, dated October 9, 1900.

Application filed September 7, 1900. Serial No. 29,346. Term of patent 14 years.

To all whom it may concern:

Be it known that we, ANTHONY DIXON BROGAN and ANDREW MURRAY MALLOCH, citizens of the United Kingdom of Great Britain and Ireland, residing at Firhill, in the city of Glasgow, county of Lanark, Scotland, have invented and produced a new and original Design for an Ornamented Sheet or Plate of Glass, of which the following is a specification, reference being had to the accompanying drawings, forming part thereof.

The design is applied to the surface of glass and is illustrated in the accompanying drawings, in which—

15 Figure 1 is a plan view of a sheet or plate of glass, showing the design. Fig. 2 is a section of the glass plate, taken as at the lines 2 2, Fig. 1.

As therein represented the design consists 20 of a ground of small pyramidal figures *a*, over or among which are a series of rosettes *b*, surrounded by flower-petals *c*, the rosettes being disposed mainly in the form of cross-figures, whose radiating arms are composed of

ovaloid scrolls *d*, filled in with parallel lines, 25 the ground being in part covered or filled in between these figures by rosettes and flower-petals. Open spaces between the flowers are filled in with lines of hatching *e*.

Black lines in the drawings represent 30 grooves or depressions or lines in intaglio of the design, and the intervening white lines or spaces represent raised lines or ridges or portions in relief of the design on the glass surface.

35

We claim—

The design for an ornamented sheet or plate of glass substantially as herein shown and described.

In testimony whereof we have signed our 40 names to this specification in the presence of two subscribing witnesses.

ANTHONY DIXON BROGAN.
ANDREW MURRAY MALLOCH.
